UNITED STATES PATENT OFFICE.

ELISHA H. SCOTT, OF RICHMOND, INDIANA.

ICELESS REFRIGERATOR.

Application filed July 21, 1924. Serial No. 727,360.

To all whom it may concern:

Be it known that I, ELISHA H. Scott, a citizen of the United States, residing at Richmond, in the county of Wayne and

5 State of Indiana, have invented certain new and useful Improvements in an Iceless Refrigerator, of which the following is a specification, reference being had therein to the accompanying drawing.

10 My invention relates to improvements in iceless, portable refrigerators, commonly known as window refrigerators, being adapted to be placed in window openings in houses; say the window of a pantry or kitchen.

15 The essential object of my invention, in order to make an iceless refrigerator, is the provision for a water supply near the top of the compartment, an absorbent basin at 20 or near the bottom and devices preferably in the nature of wicks by which water from said supply may be slowly and constantly conveyed to such basin where it is absorbed, but tends to evaporate, with the resultant 25 cooling effects. Incidentally, the water supply also tends to evaporate and in that way acts to aid in lowering the temperature within the compartment.

30 A further object of the invention consists in certain structural features, namely, the special manner hereinafter stated of forming or striking up the different plates which are to constitute the walls of the article, such as the bottom, top, back and ends, whereby 35 the cost of production will be reduced and durability of the article obtained, and whereby a refrigerator may be provided which can be shipped and stored in a knocked-down condition and readily assembled by inexperienced persons.

40 In the accompanying drawings:

Figure 1 is a vertical sectional view of my iceless refrigerator taken on the line 1—1 of Figure 2 and looking in the direction of the arrows;

45 Figure 2 is another sectional view taken on the line 2—2 of Figure 1 and looking in the direction of the arrows;

Figure 3 is a plan view of the blank of 50 which the top of the refrigerator is formed;

Figures 3^A, 3^B, and 3^C are sections on the lines A—A, B—B and C—C of Figure 3, showing the form into which the blank will be bent and some of its associated parts;

55 Figure 4 is a plan of the blank of which the end wall is formed;

Figures 4^A, 4^B, 4^C and 4^D are sections taken on the lines A—A, B—B, C—C and D—D, showing the form into which the end blank will be bent and some of its associated parts; 60

Figure 5 is a plan view of the blank of which the back of the refrigerator is formed;

Figures 5^A, 5^B and 5^C are sections taken on the lines A—A, B—B and C—C of Figure 5 showing the form into which the blank will be bent and some of its associated parts; 65

Figure 6 is a plan view of the blank of which the bottom of the refrigerator is formed;

Figures 6^A, 6^B, and 6^C are sections taken 70 on the lines A—A, B—B and C—C of Figure 6 showing the form in which the blank will be bent and some of its associated parts.

In these drawings, I have shown my improved refrigerator as having a base 1 comprised in the present instance of portions extending downwardly from a bottom 2 and reenforced by end walls 3 and back wall 4, as will hereinafter appear. The top wall 5 75 for the refrigerator compartment is preferably inclined rearwardly and is provided with an opening adapted to be closed by a cap 6 having threads which engage with threads on a collar 7. A door 8 hinged to 80 one of the end members 3 completes the enclosing of the refrigerator compartment. A member in the form of a basin having a bottom 9 and sides 9^a which may be made of any suitable absorbent material, as cement, 90 soapstone, or unglazed earthenware, is supported by the bottom 2 by directly placing the same thereon or in any other suitable manner. A container 10 for water is conveniently mounted near the top of the compartment and the desired supply of water is 95 maintained through the opening in the top of the casing referred to above. Means for conveying water slowly but constantly from the container 10 to the absorbent basin 9, in 100 the present instance wicks 11, are provided and louvres 12 in the end walls 3 permit air drafts through the refrigerator, whereby a system of evaporation will be maintained and the temperature of the compartment kept low enough for refrigerating purposes.

In case the basin 9 should absorb more water than can be thrown off by evaporation, the bottom 2 is provided with a rearwardly inclined depressed portion or groove 13 which will receive any drippings from

the basin and from which they may be readily discharged, as through an opening 14. A screen 15 is secured to that portion of the end walls having the louvres to prevent the entrance into the compartment of flies or other insects.

Trays or shelves may be arranged within the refrigerator to hold the viands it is desired to place therein and in Figure 1 I 10 have shown brackets 16 to support such trays.

Referring now to certain structural features of my invention, such as the manner of striking up or forming the walls of the 15 refrigerator compartment, as the bottom, top, back and ends, it will be seen from Figures 3 to 6 inclusive, that the blanks have been formed in such a way that the parts may be shipped and stored in a knocked 20 down condition and readily assembled by inexperienced operators and that the resulting structure will be strong and durable as well as inexpensive.

Referring first to the illustration of the 25 blank for the top 5, it comprises a substantially rectangular main portion having extensions on its margins, the extensions on the end and rear margins adapted to be folded along the dotted lines 16 back substantially 30 parallel to the main portion to form grooves, as shown in Figures 3^A and 3^C. Openings 17 in the extensions and openings 18 in the main portion register with one another for the purpose hereinafter set forth. The front 35 margin of the blank for the top 5 is folded along the dotted lines 19 so that the portion 20 will be flush with the main portion and then folded along the dotted line 21 so that the portion 22 will be at a substantially 40 right angle to the main portion and form a flange with which the upper part of the door will contact, as shown in Figure 3^B.

I will now refer to the blank for the end wall 3, the main portion of which has its 45 top slightly inclined from the front to the rear and has extensions along its margins. The extension on the top margin is adapted to be folded along the dotted line 23 at an angle to the main portion to form a tongue 50 24 which enters one of the grooves formed in the blank for the top, as shown in Figures 3^C and 4^A. An opening 25 in the tongue 24 registers with the openings 17 and 18 in the groove sections at the ends of the blank for 55 the top and receive fastening means, as shown at 26, for securing said parts together. The extensions on the rear and bottom margins of the main portion of the blank for the end 3 are bent along the dotted 60 lines 27 back substantially parallel to the main portion of the end blank to form grooves, as shown in Figures 4^B and 4^P and have openings 28 which will register with openings 29 in the assembly of the device. 65 The extension on the front margin of the

blank for the end 3 is folded at substantially a right angle to the main portion, as shown in Figure 4^C, to form a flange 30 for contact with the door 8. It will be noted that the end blanks also have portions 70 stamped to form the louvres 12 hereinafter referred to.

In Figure 5 I have shown the blank for forming the back of the refrigerator compartment substantially rectangular and having extensions at its margins, the extensions at the end margins adapted to be bent along the dotted lines 31 to form tongues 32 extending at substantially right angles to the main portion 4, as shown in Figure 5^B. 80 These tongues extend into the grooves formed by the rear margins of the end walls 3 and are provided with openings 33 which register with the openings 28 and 29 to receive fastening devices 26 to secure the parts in position relatively to one another. The extension at the rear margin of the blank for the back wall 4 is also bent at right angles to the main portion of the blank and along the dotted line 34 to form a tongue 35 90 which enters the groove formed at the rear of the top blank 5 and is secured in place by fastening means 26 passing through the openings 17 and 18 in said top blank 5 and an opening 36 in the tongue 35, as shown in Figure 5^A. The extension at the front margin of the blank for the back 4 is bent upon the dotted line 37 back substantially parallel with the main portion of the blank to form a groove, as shown in Figure 50. Openings 38 and 39 register with one another and with a corresponding opening in another blank 95 in the assembly of the device.

In Figure 6 will be seen a blank for forming the bottom wall 2 having a depressed portion 13 inclined from front to rear with an opening 14 hereinbefore referred to. The main portion of the blank is substantially rectangular in shape and has extensions at its margins each adapted to be bent downwardly at right angles to the main portion and along dotted lines 40. The bent portions at the end margins form tongues 41 which enter grooves formed by the end walls 3, as shown in Figure 6^B, while the bent portion at the rear margin forms a tongue 43 which enters the groove formed by the blank for the back wall 4 as shown in Figure 6^A. Each tongue 41 is provided with an opening 44 and the tongue 43 has openings 45 similar to the openings referred to in the other blanks and performing the same function. The bent portion at the front of the blank for the bottom 2 serves as a flange 46 for contact with the door, as shown in Figure 6^C.

Thus it will be seen that with the blanks for the several walls so fashioned they will have an interfitting relation which will permit of ready assembly by inexperienced per- 130

sons, thereby providing a device which may be shipped and stored in a knocked down condition. The ordinary refrigerator is not only bulky and the freight rate high considering the weight but requires considerable storage space. By my improved knocked down refrigerator which is light in weight, while at the same time strong and durable, the shipping expense is materially reduced 10 and the storing thereof greatly facilitated.

It will be understood that I desire to comprehend within my invention such modifications as may be necessary to adapt it to varying conditions.

15 Having thus fully described my invention, what I claim as new and desire to secure by Letters Patent, is:—

1. In an iceless refrigerator, the combination with a compartment formed of enclosing walls, some of said walls having louvres for the admission of air drafts, of

a water container near the top, an absorbent basin near the bottom, and wicks extending from the container to the basin and adapted to deliver attenuated supplies of water to 25 the basin, such water supply and basin being adapted to give off evaporation.

2. In an iceless refrigerator, the combination with a compartment formed of enclosing walls, some of said walls having 30 louvres for the admission of air drafts, of a water container near the top, means for supplying water to said container, an absorbent basin near the bottom of the compartment, water conveying means extending 35 from the container to the basin and adapted to deliver attenuated supplies of water to the basin, and means for receiving any drippings from said basin.

In testimony whereof I affix my signature.

ELISHA H. SCOTT.
